UNITED STATES PATENT OFFICE.

EDWARD C. WALLER, OF CHICAGO, ILLINOIS, ASSIGNOR TO THE LUXFER
PRISM PATENTS COMPANY, OF SAME PLACE.

DESIGN FOR A PRISM-PLATE.

SPECIFICATION forming part of Design No. 28,016, dated December 7, 1897.

Application filed October 21, 1897. Serial No. 655,971. Term of patent 14 years.

To all whom it may concern:

Be it known that I, EDWARD C. WALLER, a citizen of the United States, residing at Chicago, in the county of Cook and State of Illinois, have invented a certain new and original Design for Prism-Plates, of which the following is a description.

My invention relates to designs for prism-plates and borders.

Figure 1 is a plan view of a prism-plate and border embodying my design. Fig. 2 is a section therethrough on line 2 2.

A is the body of the prism-plate, B B the border, and C the prisms.

The border is dished away from the prisms, 15 and I have shown the border as ornamented with part open-work ornamentation.

The essential features of my design are found in a prism-plate and border comprising a body with prisms on one side and a surrounding border dished away from the prisms. 20

I claim—

A design for a prism-plate substantially as herein shown and described.

EDWARD C. WALLER.
